UNITED STATES PATENT OFFICE.

GERALD E. FORCE, OF NEW YORK, N. Y., ASSIGNOR TO HELMET CAP COMPANY, OF NEW YORK, N. Y.

RADIATOR CAP.

Application filed May 12 1922. Serial No. 560,430.

To all whom it may concern:

Be it known that I, GERALD E. FORCE, a citizen of the United States, residing at New York, in the county of New York and State 5 of New York, have invented new and useful Improvements in Radiator Caps, of which the following is a specification.

This invention relates generally to cap-retaining means of the character disclosed by 10 me in a co-pending application filed April 11, 1921, Serial Number 460,194, and principally to improvements adapting the invention to the filling caps of automobile and aeroplane motor radiators.

15 An essential object of the invention is to provide a retaining member and a radiator cap associated in a novel manner and capable of relative adjustments when in assembled relation.

20 With these and other objects in view, which will become apparent as the description proceeds, the invention resides in the construction, combination and arrangement of parts, hereinafter more fully described 25 and claimed, and illustrated in the accompanying drawings, in which like characters of reference indicate like parts throughout the several figures, of which:

Figure 1 is a view, partly in elevation and 30 partly in section, showing the radiator cap in closed position;

Figure 2 is a similar view showing the cap in open position;

Figure 3 is a vertical, central, sectional 35 view of the radiator cap; and

Figure 4 is a similar view of the cap-retaining ring.

Describing the invention in detail, 10 designates the filling neck or collar of a conventional automobile radiator having the usual threaded extension 11 for receiving cap 12. In applying the invention to the structure thus described, a retainer ring or band 13 is hingedly connected to the extension, as at 14, for swinging movement over upon the extension as in Figure 1, or to one side thereof as in Figure 2. The diameters of the extension and of the ring are the same and both members are threaded externally 45 as illustrated so that, in fact, when the extension is surmounted by the ring, the latter forms, as it were, a continuation of the threaded extension.

50 Cap 12 of the radiator is carried by ring 13, which screws into the cap as shown in

the drawings. The threaded portion of the cap, it will be noted, is thickened to provide shoulder 15 which is engaged by lugs 16 of the retaining ring to prevent separation of the ring and cap. Lugs 16 are integral with ring 13 and are bent at right angles to the ring subsequent to the screwing of the latter into the radiator cap. Any suitable implement may be employed for bending the lugs to which access may be conveniently had through the opening in the ring.

When the cap is in closing position over the filling orifice of the radiator it may be readily screwed down onto extension 11 and past the threads of ring 13 as seen in Figure 70 1. When the cap is unscrewed and swung to one side, as in Figure 2, it may not however be turned back past the threads of the retainer rings, since lugs 16 of the latter abut shoulder 15 and prevent further unscrewing of the cap. Hence, the absolute separation of the cap and ring is prohibited and the liability of losing or misplacing the cap is prevented.

Radiator caps of the general type now 80 in use have proven unsatisfactory owing to their prevalence for being misplaced when filling the radiator, and the further fact of becoming disengaged or lost owing to the vibration of the motor. Especially is the 85 latter true in connection with aeroplane motors, and it was to overcome these deficiencies as well as others, that I have designed the form of closure forming the subject matter 90 of this invention.

In practice, I have found that the form of my invention illustrated in the accompanying drawings and referred to in the above description, as the preferred embodiment, is the most efficient and practical; yet realizing the conditions concurrent with the adoption 95 of my device will necessarily vary, I desire to emphasize that various minor changes in details of construction, proportion and arrangement of parts, may be resorted to within the scope of the appended claims without departing from or sacrificing any of the principles of this invention.

Having thus described my invention, and without enumerating variations and equivalents, what I desire protected by Letters Patent is as set forth in the following claims:

1. The combination with a radiator filling neck and an internally shouldered cap adapted to fit thereover, of a cap-retaining mem- 110

ber contained within the cap and held against separation therefrom by engagement with said shoulder, and a connection between the retaining member and neck permitting the retaining member to be moved to positions overlying or lateral of the neck.

2. The combination with a radiator filling neck, of a cap adapted to fit thereover and provided with an internal shoulder, a retaining member contained within the cap in reciprocal engagement therewith, lugs on the retaining member engageable with said shoulder, and a connection between the retaining member and neck adapted to permit movement of the retaining member to positions overlying or lateral of the neck.

3. The combination with a radiator filling neck provided with an external thread of an internally threaded cap, adapted for engagement therewith, a retaining member threadedly engaged in said cap and adapted to be

substantially concealed thereby, means hingeably connecting the retaining member to the neck, and lugs on the retaining member engageable with the cap to hold the latter against separation therefrom.

4. The combination with a radiator filling neck, of an internally shouldered cap adapted to fit over said neck, a retaining member in the form of an open-centered ring inserted in said cap in reciprocal engagement with the inner wall thereof, a lug projecting from the lower edge of the retaining member pivotally secured to said neck and lugs projecting from the upper edge of the retaining member engageable with the internal shoulder of the cap.

GERALD E. FORCE.
